TABLE ORNAMENT

Russell Webster Olson, Eau Claire, Wis.

Application September 24, 1948, Serial No. 148,754

Term of patent 3½ years

(Cl. D29—1)

To all whom it may concern:

Be it known that I, Russell Webster Olson, citizen of the United States of America, residing at Eau Claire, in the county of Eau Claire and State of Wisconsin, have invented a new, original, and ornamental Design for a Table Ornament, of which the following is a specification, reference being made to the accompanying drawing, forming a part thereof, wherein the single figure is a perspective view of a table ornament, illustrating my new design.

The opposite side of the tree or ornament is plain in appearance.

I claim:

The ornamental design for a table ornament, as shown, and described.

RUSSELL WEBSTER OLSON.
